(57) **CLAIM**

We claim the ornamental design for a surgical connector, as shown and described.

DESCRIPTION

FIG. 1 is a top, front and right side perspective view of an electrical connector showing our new design;

FIG. 2 is a top plan view thereof;

FIG. 3 is a right side elevation view thereof;

FIG. 4 is a bottom plan view thereof;

FIG. 5 is a left side elevation view thereof;

FIG. 6 is a front elevation view thereof; and,

FIG. 7 is rear elevation view thereof.

The broken lines showing portions of a surgical connector are for the purpose of illustrating environmental structure and form no part of the claimed design.
